Baldwin Son

United States Patent Office.

JOSEPH NEWHAM, OF KENT, OHIO.

Letters Patent No. 66,246, dated July 2, 1867.

IMPROVED RAILWAY RAIL-COUPLING.

The Schedule referred to in these Letters Patent and making part of the same.

TO ALL WHOM IT MAY CONCERN:

Be it known that I, JOSEPH NEWHAM, of Kent, in the county of Portage, and State of Ohio, have invented a new and useful improvement in Coupling Railroad Rails; and I do hereby declare that the following is a full, clear, and exact description of the construction and operation of the same, reference being had to the annexed drawings, making a part of this specification, in which—

Figure 1 represents in perspective the ends of two rails with my invention applied to couple and hold them together.

Figure 2 represents in perspective my coupling detached from the rails.

Figures 3 and 4 represent in perspective the parts of my coupling separate; and

Figures 5 and 6 represent in perspective the ends of two rails prepared to have my coupling applied.

It is the object of my invention in coupling rails to hold them rigidly and truly in line, while leaving them free to contract and expand longitudinally without interrupting the joint, and to keep them truly horizontal, with the minimum depression at the ends; and to this end my invention consists in notching the ends of the rails transversely beneath the tread, and placing within the notches a nicely fitting bar, having a fixed head to match the curvature of the web of the rail on one side, and a slotted washer to match the curvature of the web on the other side, with a square draw-hole punched through the bar on the outside of the slotted washer to receive a spike which draws the fixed head and washer close upon the ends of the rails, and fastens the rail ends securely to the cross-tie on which they meet.

To carry out the objects of my invention I cut the ends of the rails A and B perpendicularly to match each other, and notch them at C and D transversely by severing the web in its thinnest portion, taking care that the edges of the notch in one rail register truly with the edges of the notch in the other, and that the surfaces of the notch above and below are parallel to each other. I now form a block, E, having its outer side a vertical, while its inner side b is curved to match the depression c of the rail, of whatever form the rail may be. To the block E a bar, F, is firmly secured so as to let the curved side of the block E fit neatly the depression on the rail, while the bar F fills neatly and fits truly the notches C and D in the ends of the rails. The bar F has a square draw-hole, d, punched in its outer end that a spike may be inserted into. A washer, G, is formed to fit the depression of the rail on one side, and in a plane on the other for the spike H to rest against and press upon the full width of the outside of the washer. The lower edges of the rail ends have on one side notches f and k cut in them, so that when the ends are brought together the spike may pass into the cross-tie in contact with the washer G; and when a metal chair is used for the ends of the rails to rest on, the chair must also be punched to permit the spike to enter the ties.

The operation of my invention is as follows: The ends of the rails being brought together upon a chair or cross-tie the bar is inserted in the notches or slot in the ends of the rails, and pushed up until the curved side of the block, to which the bar is attached, comes snugly into the curve of the rail. The washer is then placed on the bar with its curved side toward the rail, and it is pushed into contact with the rail, when the spike is inserted and driven home. This at once clamps the ends of the rails together securely, as seen in fig. 1, and the spike holds both the rails, and when one is used, the chair securely in place, while the contraction and expansion of the rails longitudinally remain uninterrupted. At the same time the removal of a thin web from the centre of the ends of the rails, and the substitution of the thick and more condensed bar therefor, strengthens the ends of the rails and supports the tread against undue depression, and preserves its surface nearly uniform with that of the other portions of the rail.

It is obvious that my block, bar, and washer may be made cheaply of wrought iron in proper swages, or that cast iron rendered malleable may in many situations be used for these parts with marked economy, and without any material diminution of the strength of the coupling; or the block and washer may be cast, and the bar be of hammered iron. It is also evident that the spike which holds the rails together will secure both them and the chair in place upon the tie, and thus one spike will be saved when a chair is used for the ends of the rails to rest upon.

What I claim as my invention, and desire to secure by Letters Patent, is—

1. The combination of the bar, block, and washer with the ends of the rails and spike, substantially as and for the purpose set forth.

2. Securing the ends of railroad rails in position, substantially as and for the purpose set forth.

In testimony whereof I have hereunto subscribed my name.

Witnesses:

FRANCIS L. SAWYER,
WILLIAM GRINNELL.

JOS. NEWHAM.
